U.S. Cl. D83—1

FIG. 1

FIG. 3

FIG. 5

FIG. 2

FIG. 4

FIGURE 1 is a rear perspective view of a mobile X-ray apparatus, or similar article, showing my new design;

FIG. 2 is a rear elevation view thereof;

FIG. 3 is a front elevation view thereof;

FIG. 4 is a side elevation view thereof, the opposite side is substantially the same as the side shown; and

FIG. 5 is a top plan view thereof.

The broken lines illustrating an X-ray tube housing and electrical cables are shown for purposes of illustration only.

The dominant features of my design reside in the portions shown in full lines.

I claim:

The ornamental design for a mobile X-ray apparatus, substantially as shown and described.
